MACHINE FOR MAKING ROOFING TILES
AND LIKE ARTICLES

Otto Walter, Perrysville, Ind.

Application September 25, 1931
Serial No. 565,059

13 Claims. (Cl. 25—41)

The object of this invention is to provide a machine for the rapid and economical production from cement, or other similar material of roofing tiles and the like of superior quality and texture adapted for general use in place of wood and composition shingles or the old-style shingles or tiles. As to rapidity of production, the machine herein shown can make about 150 tiles a minute or 9,000 an hour, which greatly reduces the cost 10 thereof.

In the manufacture of tiles by machines heretofore, particularly of cement, there has been a double problem, namely, to sufficiently mix the cement or other material for the tile so that the 15 tile will be substantially uniform in character and to eliminate air bubbles which render the tiles weak and variable in character. The two foregoing phases of the problem involved have been satisfactorily solved by the machine herein shown and described, in addition to the very rapid and inexpensive production of the tiles.

Aside from the above, the machine is adapted to produce a tile of beautifully blended colors when supplied with a variously colored mix.

The principal feature of the invention consists in the means for agitating the cement or mix in the mold box between the mold plates. The said means consists of vertically disposed agitating fingers being rapidly reciprocated vertically in the material between each pair of mold plates, whereby the cement or other material is more uniformly mixed and the air bubbles that would be liable to weaken the tile or render the tiles variable in strength are eliminated. The 35 puddling action of the fingers also causes the surface of the tile to be smooth and hard. For this purpose, the agitating fingers are preferably reciprocated about 100 times a minute with a twelve inch stroke.

Further features of the invention consist in means, such as a tooth bar with teeth for guiding the lower ends of the agitating fingers into the mold box in proper position between the mold plates therein and withdrawing said tooth bar 45 during the vertical reciprocation of the agitating fingers. Also, there are two carriages mounted in the framework, a lower one carrying the agitating fingers which are adapted to be vertically reciprocated, and an upper carriage for carrying the means for vertically reciprocating the lower carriage, and tension springs for supporting the lower carriage from the upper carriage, means for holding said carriage unit in upper and idle position and for holding the upper carriage down when in operating position, and

means for elevating said carriages at the end of the operation.

The full nature of the invention will be understood from the accompanying drawings and the following description and claims:

In the drawings, Figure 1 is a front elevation of the machine with a portion of the top broken away. Figure 2 is an elevation of the left-hand end of the machine showing the mechanism in its idle position. Figure 3 is the same view of the machine as that shown in Figure 2 with the parts of the machine in operating position, a concrete hopper being shown by dotted lines in dumping position. Figure 4 is a vertical section of the upper part of the machine substantially central and longitudinal of the machine with parts broken away. Figure 5 is a horizontal section of the machine on the line 5—5 of Figure 4. Figure 6 is an elevation of one end of the concrete charging chute, parts being in section. Figure 7 is a horizontal section through a portion of the mold box during the agitating operation. Figure 8 is a vertical section through a portion of the mold box on the line 8—8 of Figure 7, showing the agitating fingers in their down position during the agitating operation. Figure 9 is the same showing the upward limit of the agitating fingers during the agitating operation.

The apparatus shown herein includes substantially three parts, a mold car 10, a concrete hopper 11, and the main body of the machine which constitutes this invention. The machine is mounted on a pair of front uprights 12 and a pair of rear uprights 13 and the mold cars are rolled between said uprights under the main part of the machine, as seen in Figures 1 and 2, for charging the same with concrete and molding the concrete roofing tiles.

In the operation of this machine, a large number of the mold cars 10 are employed and each is in the nature of a truck-shaped lower portion and a mold box 14. As shown here, the mold box and truck are secured together as a unit, but so far as this invention is concerned, they may be separated, the mold box being placed upon the truck. The mold box has its sides hinged to the truck at 15, whereby the sides thereof can be readily let down for unloading the same. Within the mold box a large number of removable mold plates 16 similarly formed are placed with their lateral edges adjacent each other. In the mold boxes so far built, there are two rows of these mold plates, one in each side of the box, as shown in Figure 7, and there are

75 mold plates in each side, making a large enough number of mold plates to mold 150 roofing tiles simultaneously and in one operation of the machine. The top of the mold box 14 is 5 open and the concrete is dumped downward therein so as to fill all of the spaces between the mold plates and form the roofing tiles 18, as seen in Figure 7.

In making roofing tiles of concrete and like 10 material, it is desirable that they be sufficiently strong and light in weight. The usual tile is about 15 inches long, 9 1/4 inches wide, 1/8 of an inch thick in the thicker portions and about 1/16 of an inch thick in the thinner portions, although 15 the invention is not limited to any particular size or shape of roofing tile and the like. If the tile has in it relatively large air bubbles, it will be weak because the tile must obviously be relatively thin. Therefore, in making roofing tile 20 of concrete, cement or like material, the problem is presented to eliminate the relatively large air bubbles from the concrete between the mold plates in the mold box. This problem is solved in this invention by employing vertically movable 25 agitating fingers 20 insertable in the cement while the cement is being molded, and very rapidly moving said fingers up and down. By this method and means, the air bubbles will be eliminated. The fluidity of the mix is such that the 30 rapid operation of the agitating fingers, when inserted at the center of the type of mold shown in Figure 7, is sufficient to affect the entire tile. Aside from the elimination of the air bubbles, the action of the fingers completes the mixing 35 of the ingredients to produce a homogeneous mass throughout the tile. It "puddles" the mass so that the most finely divided particles come to rest against the surfaces of the mold plates and thereby produce a smooth, hard surface when 40 the tile is cured. It also causes a blending of colors to produce a beautifully variegated tile when a variously colored mix is used.

The frame of this machine, as stated, consists 45 of the uprights 12 and 13 secured at their lower ends to a frame 21, or equivalent means, and having front cross bars 22 and 23 and end cross bars 24 and 25 at each end of the machine. In this stationary main frame, two vertically- 50 movable carriages are provided, a lower carriage for the agitating fingers 20, and an upper carriage with means for vertically reciprocating the lower or finger carriage.

The upper carriage consists of a cross bar 28 55 at each end of the machine whose down turned ends are vertically slidable between guide bars 26 fastened to the main frame and a cross shaft 60 mounted thereon by means of bearings 61. The downward movement of said upper carriage is limited by stop bars 29 secured thereto and 60 adapted to engage the stationary cross bars 25 of the main frame.

The lower carriage includes a pair of upper 65 cross bars 30 at each end of the machine to each of which a lower cross bar 31 is connected by vertical bars 32 sliding between the guide bars 26. To each of the bars 30 there is fastened an angle member 33 and they support four horizontal members 36 extending longitudinally of the machine which carry the agitating fingers 70 20 preferably welded or soldered thereto. As will be best seen in Figure 5, there are two rows of the said agitating fingers, one for each of the two rows of molds in the mold box 14. The upper and lower carriages are connected by 75 springs 87 so that they coact as a unit to some

extent, and yet the lower or finger carriage has the desired independent vertical movement, as will hereafter appear.

The agitating fingers in this machine are about 19 inches long and one inch wide and 1/16 of an 80 inch thick, their lower ends being substantially free, as shown in Figure 4, but they must be guided when they descend to prevent them from hitting the tops of the mold plates 16. This is accomplished by guide teeth 40 on a tooth bar 41 arranged for each row of fingers 20. The two tooth bars, as seen in Figures 2 and 5, are 85 slideable forwardly and rearwardly between guide members 43 supported upon the main frame by cross pieces 44 and are connected by tension 90 springs 42 which normally draw the tooth bars 41 toward each other. In the upper position of the finger carriage, the teeth 40 engage the lower 95 ends of the fingers 20 to guide the same between the mold plates. As this carriage is lowered, the tooth bars 41 are moved away from the fingers 20 by means of a pair of frames 45 which are supported by the cross members 36 and which engage rollers 46 carried upon the 100 ends of the tooth bars 41. As best shown in Figure 2, the lower ends of the frames 45 are inwardly bent to permit the springs 42 to draw the tooth bars into position to guide the fingers, while the upper portions thereof are widened to 105 engage the rollers to push the tooth bars away from the fingers 20 so that the said tooth bars are out of the way during the agitating movement of the fingers hereinafter explained.

In order that the lower ends of the fingers 20 may enter properly between mold plates 16 110 in the mold box 14, it is necessary that the mold car 10 with the mold box thereon shall be accurately positioned under the machine above described. To that end, the mold boxes have on their sides guide bars 48 adapted to engage rollers 49 mounted on a stationary frame bar 50 secured to the stationary frame uprights 12 and 13. To locate the mold box in the other direction properly, there is a catch 51 about central 115 of the front side of the mold box adapted to be engaged by a latch bar 52 mounted on the stationary frame bar 50, as seen in Figures 1 and 2, for predetermined and holding the box in a satisfactory position to register accurately with the fingers 20.

The power for driving the agitating fingers of this machine comes from a motor 53, seen in Figure 1, which drives a belt 54 and pulley 55 secured on a shaft 56 with bearings on the uprights 12 at each end of the machine. A pulley 57 through a belt 58 drives a pulley 59 secured on the shaft 60 mounted in bearings 61 on the tops of the end cross bars 28 and forming said upper carriage. At the ends of shaft 60, there are crank discs 62 to which are connected connecting rods 63, the lower ends of which are pivoted to the bars 31 at 64 for the vertical reciprocation of the finger-carrying carriage.

The upper and lower carriages and springs 87 connecting them are almost counter-balanced by 140 a weight 65 on a lever 66 which is fulcrumed between its ends at 67 on the top of the main frame and which has its inner end connected by a link 68 with a lug 69 on the bearings 61.

The carriages are lifted from the lower agitating position shown in Figure 3 to the upper and idle position shown in Figure 2, by means of a rope 70 which is loosely connected with the shaft 60 at 71 and extends over a sheave 72, as seen at 145 the upper right-hand corner of Figure 1, and is 150

coiled a few times about the shaft 56. When the free end thereof at 73 is grasped by the hand of the operator and pulled to tighten the coil on the revolving shaft 56, the latter shaft winds up the 5 rope and raises the shaft 60 and the carriages with which it is connected. This upward movement of the carriages is stopped when stop plates 33 fastened to the bars 30 reach the cross members 25 of the main frame.

10 The mode of operation will now be explained together with the control means. After the mold car and box have been pushed under the machine and locked in proper position and while the carriages and agitating fingers 20 are in their upper 15 position, the operator pulls a handle 75 which is pivoted to the underside of the concrete hopper 11 at 76. This opens a gate 77 in a chute 78 which permits the concrete or other mix to pass from the hopper 11 down through the chute 78 20 into the mold box 14 until it fills the spaces between the mold plates 16. Then the gate 77 is closed.

The chute 73 is preferably formed as best shown in Figure 6. A fixed portion marked 78a 25 forms the two ends and one side of the chute, the ends being only a few inches wide and the side extending for the full length of the mold box. The second side of the chute is formed by a removable plate 79 having end members 79a 30 overlapping the end portions of the fixed member 78a and formed with inclined slots 80 engaging pins 81 carried on the said end portions. The plate 79 can then be lifted from the pins 81 to permit removal for cleaning the interior of the 35 chute.

In the operation, the next step is for the operator to lower the two carriages carrying the fingers 20 and reciprocating means. This is done by the operator pushing rearward on a hand lever 40 82, seen at the right-hand central portion of Figure 1. The said lever is pivoted between its ends at 83 to a bracket 84, and the upper end, as seen in Figure 2, is pivoted to a cross bar 35 that is pivoted to a latch bar 86 that catches under one 45 of the angle irons 36 to which the fingers 20 are secured. The said latch bar supports the lower carriage and fingers in their upper and idle position (Figure 2), while the upper carriage is maintained in its upper position by the connecting rods 63. When the lever 82 is actuated, it unlatches the latch bar 86 and permits the carriages to descend, the upper carriage assuming the position shown in Figure 3, resting upon the frame members 25, and the lower carriage carrying the 50 fingers 20 being supported by the tension springs 87 some distance above the position shown in Figure 3. The tension springs 87 are able to perform this function since at this point in the operation the belt 58 is loose and the crank discs 62 are free to rotate. In this position, the fingers have entered between the mold plates in the mold box and the tooth bars 41 have been moved away from the fingers.

55 The operator then locks down the upper carriage by pulling down a hand lever 90. The lever 90 is secured to a shaft 91 that extends forward and rearward of the machine in a bracket 92 at the left-hand side, as shown in Figure 1. On said rod 91 there are two downwardly-extending fingers 93, as appears in Figures 1, 2 and 4, which engage a lug 94 on the inside of the cross bar 23 of the upper carriage. The other end of said upper carriage is locked by similar stop fingers 193 which are secured on a shaft 190, at the right-hand side of Figure 4. The shaft 190 is operated

by a crank 95 which is operated by a connecting rod 96 running from a crank 97 secured on shaft 91 at the left-hand side of Figure 4.

The next step is to set in motion the vertical reciprocation of the lower carriage and fingers 20. This is done by changing a lever 100, seen in Figure 2, from the position there shown to the position shown in Figure 3, in order to tighten the belt 58 for transmission of power from the pulley 57 to the pulley 59, which, through the 80 shaft 60, drives the crank disc 62 and reciprocates the lower carriage and the agitating fingers 20. Said lever 100 is fulcrumed between its ends at 101 to a bracket on the side of the left-hand upright 12, and its inner end carries an 85 idle pulley 102 that engages the belt 58. Said belt tightening mechanism is locked in belt-tightening position by a lock bar 103 pivoted between its ends to the lever 100 at 104. The lock bar 103 is provided with a pair of notches on 90 the underside, one of which engages the bracket 92, as shown in Figure 3, to hold the lever 100 in operating position, and the other of which engages a plate 106 secured to the lever 90, as shown in Figures 1 and 2 to hold the lever 100 in 95 non-operating position. The notched bar is held in engagement by a spring 105, seen in Figure 3, connecting the lock bar 103 with the lever 100. When the lever 90 is pulled down, the plate 106 thereon disengages its notch in the lock bar 103 100 which enables the lever 100 to be operated, and when operated to be locked by engagement of the other notch with bracket 92.

The apparatus is now in position to vertically reciprocate the lower carriage with agitating 110 fingers 20, which is accomplished through the crank discs 62. The crank discs make a 12-inch stroke and, in the machine shown, they make about 100 revolutions a minute which reciprocates the agitating fingers from the upper position shown in Figure 9 to the lower position shown in Figure 3, and back again. This very rapid agitation of the concrete or other mix between the mold plates in the mold box is such as to 115 cause practically all of the air bubbles to be eliminated. Of course, obviously the speed of the fingers and the fluidity of the concrete would cause slight variations in the operation and effect of the fingers. The greater the fluidity of 120 the concrete, the more rapidly is the elimination of the air bubbles accomplished. Another effect of the fingers is the puddling effect, whereby the concrete is not only more thoroughly mixed and rendered uniform in texture, but the surfaces of 125 the tile are rendered smooth and hard when dried.

The agitating process requires less than one minute in the machine herein shown and then the lever 90 is operated and that releases the 130 lock bar 103 and lever 100 which returns the belt tightener to the inoperative position shown in Figure 2, shuts off the power and also releases the stops 93 so that the carriages and fingers may be elevated. Then the operator pulls 135 the end 73 of the rope 70, as has been explained, and thereby raises the carriages from the position shown in Figure 3 to that shown in Figure 2. When the latch 23 catches below the cross bar 36, it locks them in their upper and inoperative position.

The car latch 52 is then released and the mold car or box is wheeled out into a place for the tiles to be cured and, after they are sufficiently cured, the tiles are removed. As soon as one mold box 150 is moved from its place below the machine, an-

other is substituted, and thus, with the machine herein shown, 150 roofing tiles may be made every minute or 9,000 an hour.

The invention claimed is:

5 1. Mechanism for molding products of concrete and the like in open top molds, including an upper carriage adjustable between an upper and a lower position, a lower carriage yieldingly supported by said upper carriage, agitating fingers extending down from said lower carriage and adapted to enter and reciprocate within the molds, and means mounted in said upper carriage for vertically reciprocating the lower carriage when in its lower position.

15 2. Mechanism for molding products of concrete and the like in open top molds, including a vertically-reciprocable lower carriage above the molds, agitating fingers extending down from said carriage and adapted to enter and reciprocate within the molds, a vertically-adjustable upper carriage above said lower carriage, mechanism carried upon said upper carriage and connected to said lower carriage for reciprocating the latter and the fingers carried thereby, and means for lifting said upper carriage to remove said fingers from the mold.

30 3. Mechanism for molding products of concrete and the like in open top molds, including a vertically-reciprocable lower carriage above the mold, agitating fingers extending down from said carriage and adapted to enter and reciprocate within the molds, a vertically-adjustable upper carriage above said first carriage, a resilient connection between said carriages for resiliently supporting said lower carriage from said upper carriage, mechanism for rapidly reciprocating said lower carriage and the fingers carried thereby when said upper carriage is in its lowermost position, and means for lifting said upper carriage whereby said lower carriage is elevated by means of said resilient connection to lift said fingers from the molds.

45 4. Mechanism for molding products of concrete and the like in open top molds, including a vertically-reciprocable lower carriage above the molds, agitating fingers extending down from said carriage and adapted to enter and reciprocate within the molds, a vertically-adjustable upper carriage above said first carriage, a resilient connection between said carriages for resiliently supporting said lower carriage from said upper carriage for rapidly reciprocating said lower carriage and the fingers carried thereby when said upper carriage is in its lowermost position, and means for lifting said upper carriage whereby said lower carriage is elevated by means of said resilient connection to lift said fingers from the molds.

50 5. Mechanism for molding products of concrete and the like in open top molds, including a vertically-reciprocable lower carriage above the molds, agitating fingers extending down from said carriage and adapted to enter and reciprocate within the molds, a vertically-adjustable upper carriage above said lower carriage, a shaft carried upon said upper carriage, a crank mounted on said shaft, a connecting rod connecting said crank to said lower carriage for reciprocating the latter and the fingers carried thereby by the rotation of said shaft, and means for lifting said upper carriage for elevating said lower carriage to withdraw the fingers from the molds.

55 6. Mechanism for molding products of concrete and the like in open top molds, including a

vertically-reciprocable lower carriage above the molds, agitating fingers extending down from said carriage and adapted to enter and reciprocate within the molds, a vertically-adjustable upper carriage above said lower carriage, a shaft carried on said upper carriage, a crank mounted on said shaft, a connecting rod connecting said crank to said lower carriage for reciprocating the latter and the fingers carried thereby by the rotation of said shaft, means for lifting said upper carriage for elevating said lower carriage to withdraw the fingers from the molds, and tension springs connecting said carriages and normally tending to elevate said lower carriage but permitting said rapid reciprocation thereof.

80 7. Mechanism for molding products of concrete and the like in open top molds, including a vertically reciprocable lower carriage above the molds, agitating fingers extending down from said carriage and adapted to enter and reciprocate within the molds, a vertically adjustable upper carriage above said first carriage, a shaft carried upon said second carriage, a crank mounted on said shaft, a connecting rod connecting said crank to said lower carriage for reciprocating the latter and the fingers carried thereby by the rotation of said shaft, means for lifting said upper carriage for elevating said lower carriage to withdraw the fingers from the molds, tension springs connecting said carriages and normally tending to elevate said lower carriage, 95 power means for rotating said shaft to reciprocate said lower carriage and fingers, and means for disconnecting said power means from said shaft to permit said tension springs to elevate 100 said lower carriage when said upper carriage is elevated.

9. Mechanism for molding products of concrete and the like in open top molds, including a vertically adjustable upper carriage, a lower carriage 115 reciprocably supported from said upper carriage, agitating fingers extending down from said lower carriage and adapted to enter and reciprocate within the molds, means for raising the upper carriage for withdrawing the fingers from the 120 molds and for lowering the same to permit said fingers to enter the molds, a latch engaging said upper carriage at each end thereof for locking said upper carriage in its lowermost position, a lever, and connections between said latches and 125 said lever for operating both of said latches by movement of said lever.

9. Mechanism for molding products of concrete and the like in open top molds, including a vertically adjustable upper carriage, a lower carriage 130 reciprocably supported from said upper carriage, agitating fingers extending down from said lower carriage and adapted to enter and reciprocate within the molds, means for raising the upper carriage for withdrawing the fingers from the 135 molds and for lowering the same to permit said fingers to enter the molds, and a latch for locking said upper carriage in its uppermost position, said latch automatically engaging a portion of said upper carriage when said uppermost position 140 is reached.

10. Mechanism for molding products of concrete and the like in open top molds, including a vertically reciprocable carriage, agitating fingers extending down from said carriage and adapted to enter and reciprocate within the molds, means for raising the carriage for withdrawing the fingers from the molds and for lowering the same to permit said fingers to enter the molds, a tooth bar immediately above the molds with a series 145

- of guide teeth for guiding the lower ends of the fingers into the molds, and means for vertically reciprocating the carriage while the fingers are within the molds. 80
- 5 11. Mechanism for molding products of concrete and the like in open top molds, including a vertically reciprocable carriage, agitating fingers extending down from said carriage and adapted to enter and reciprocate within the molds, means for raising the carriage for withdrawing the fingers from the molds and for lowering the same to permit said fingers to enter the molds, means immediately above the molds for guiding the lower ends of the fingers into the molds, mechanism for withdrawing said guiding means from the fingers after the latter have entered the molds, and means for vertically reciprocating the carriage while the fingers are within the molds. 85
- 10 12. Mechanism for molding products of concrete and the like in open top molds, including a material hopper, a chute of elongated cross section extending from said hopper and adapted to deliver material to said molds, said chute ex- 90
- 15 20 25 30 35 40 45 50 55 60 65 70 75 80 85 90 95 100 105 110 115 120 125 130 135 140 145 150
- tending longitudinally and centrally of said molds, a row of agitating fingers on each side of said chute adapted to enter and reciprocate within the molds, and means for reciprocating said fingers while in the molds. 13. Mechanism for molding products of concrete and the like in open top molds, including a vertically movable upper carriage, a lower carriage reciprocably supported upon said upper carriage, agitating fingers extending down from said lower carriage and adapted to enter and reciprocate within the molds, power means for reciprocating said lower carriage, control mechanism for connecting and disconnecting said power means, a latch bar for locking said control means in operative position, locking means for locking said upper carriage in lowermost position with the fingers within the molds, and a connection between said locking means and said latch bar by means of which said latch bar is tripped to disconnect said power means when said locking means is unlocked. 95
